SNOW REMOVING BOARD

George H. Yates, 37 Hill St., Ellicott City, Md.

Filed July 23, 1963, Ser. No. 75,935

Term of patent 14 years

(Cl. D39—1)

FIG. 1 is a perspective view of a snow removing board incorporating my new design;

FIG. 2 is a rear elevation showing the side opposite from the side of FIG. 1;

FIG. 3 is a side elevation thereof;

FIG. 4 is an end elevation thereof;

I claim:

The ornamental design of a snow removing board, as shown.
